UNITED STATES PATENT OFFICE.

ADOLF LUDI, OF GRENCHEN, SWITZERLAND.

THERMOSTATIC CIRCUIT CLOSER.

Application filed July 14, 1921. Serial No. 484,791.

To all whom it may concern:

Be it known that I, ADOLF LUDI, a citizen of Switzerland, and residing at Grenchen, Canton of Solothurn, Switzerland, have invented certain new and useful Improvements in Thermostatic Circuit Closers, of which the following is a specification.

The present invention relates to a thermostatic circuit closer as used for vulcanizing apparatus of the kind where a spring effects the open position of a contact lever.

The novel feature of the invention resides in a thermostatic bar which in its cold state maintains the contacting position of the lever, but will cause the open position of the lever after a certain time when said bar gets bent by the heat of an electrical resistance.

The annexed drawing shows one example 20 of the device as applied to a vulcanizing apparatus.

Fig. 1 is a plan,

Fig. 2 a cross section and

Figs. 3 to 7 relate to details and

25 Fig. 8 is a diagram of the electrical connections.

In a vulcanizing apparatus according to Figs. 1 to 8 the cover 1 of the upper press plate 3 shows a recess in which is inserted 30 an electrical resistance 2. This cover serves as bed plate of the whole apparatus and is cast in one piece with a channel-shaped hood 4 open at both ends having a shoulder 7 inside of this hood and with a casing 6 35 having a removable cover plate 5. A bar 8 composed of two parallel metal strips soldered one above the other and having a different coefficient of expansion is screwed fast with one end by a screw 9 onto the 40 shoulder 7 and carries at its other end which is projecting into the casing 6 a stud 10. This stud penetrates into a slot 12 provided within a gudgeon 11 fast on the wall of the casing and projects not only to the 45 outside of the cylindrical surface of said stud, but also outside of a sleeve 14, so that a flat spring 15 fixed to an arm 13 which is mounted rigidly on said sleeve and rotatably with the same on gudgeon 11 will 50 rest with its sharp edge against said stud 10, which fact will prevent said arm 13 from being swung upwards under the effect of the helical spring 16 interposed between 55 cover and lever.

In order to have arm 13 freely oscillating within certain limits the sleeve 14 is pro-

vided with a slot for the stud 10. The contact of arm 13 with contact screw 25, 22, 21 is obtained by a strip 17 which is electrically insulated from the arm and fixed 60 to it and is electrically connected to a terminal 19 of a source of electrical current by a conductor 18 passing through the wall of casing 6. The other terminal 20 of the source of electrical current connects to one 65 end of the plate resistance 3, the other end of which connects with an insulated screw 21. This screw by means of a resilient contact strip 22 and a knob 25 attached to it will come into contact with a knob 24 70 provided on strip 17. Plate resistance 3 is completely surrounded by insulating sheets of mica so as to have no current in the casing and plates. A pusher 23 guided within cover 5 is provided above the place 75 of coupling between strip 17 and arm 13 and a stop pin 29 is fixed to cover plate 1 underneath arm 13 in order to prevent too great a compression of springs 16 and 22, when the pusher is depressed in order to 80 establish the contact position between strip 17 and the resilient strip 22.

The working of the thermostatic circuit closer is obtained by heating the plate resistance 2 by an electric current coming in 85 at the terminals 19, 20. The bar 8 will be heated with the whole apparatus and as the metallic strip of greater dilatation is on the upside of the bar, this bar will bend downwards when getting hot. Stud 10 will 90 begin to sink and at the very moment, when spring 15 has lost its catch on said stud, the arm 13 will snap upwards under the effect of spring 16, thus breaking suddenly the contact at 24, 25 and stopping the heating 95 and vulcanizing process.

In order to have some regulating means of the time of heating of the apparatus an axle 30 journalled within the walls of hood 4 is arranged underneath the bar 8 between 100 casing 6 and shoulder 7, said axle bearing with an eccentric 26 against the bar, so as to have the bar and with it the stud 10 lowered or raised to some small amount, whenever the axle is turning, and to accelerate or retard the withdrawal of said stud from its contact with the flat spring 15.

An index 31 is mounted on the axis and a stopping pin 27 for limiting the movement of this lever is fixed on the plate 1. 110 This index indicates on a graduation 28 provided on the outside wall of hood 4 the

amount of turn given to the axle 30 when adjusting the working of the bar 8.

What I claim as new, and desire to secure by Letters Patent, is:

- 5 1. A thermostatic circuit closer comprising a stationary contact, a slotted gudgeon, a contact arm of a switch sleeved with a slotted end on said gudgeon a pusher for moving the contact arm to contacting position, a spring resting against said arm biasing it to open position, a bar compounded of two parallel metal strips of different coefficient of expansion passing close to said slotted sleeve and kept fast at one end so as
- 10 15 to bend, when getting heated, a stud fixed to the free end of said bar, traversing the slotted gudgeon and the slotted sleeve and projecting beyond the sleeve, and a flat spring fast to said arm resting with a sharp edge against the projecting end of the stud, but left free at the withdrawal of the same by the bending bar, and adapted to slip over the replaced stud when the arm is brought back again by said pusher into its contacting position.

- 20 2. A thermostatic circuit closer comprising a slotted gudgeon, a contact arm of a switch sleeved with a slotted end on said gudgeon, a pusher for moving the contact arm to contacting position, a spring biasing it to open position, a compound bar having two metal strips of different coefficient of

expansion and arranged so as to bend when getting heated, a stud fixed to said bar and traversing the slotted gudgeon and the slotted sleeve of the arm, a flat spring fast to said arm and catching with a sharp edge the projecting end of the stud in the contact position of the switch, and means for regulating the amount of catch between 40 stud and flat spring and thereby the time of tripping of the switch.

3. A thermostatic circuit closer comprising a slotted gudgeon, a switch arm arranged rotatably with a sleeved and slotted end on said gudgeon, a compound bar adapted to bend when getting heated, a stud fixed to said bar and traversing said gudgeon and said slotted sleeve, a flat spring fast to said arm and catching the projecting end 45 of the stud in the contact position of the arm, and means for regulating said catch, comprising, a journalled axle arranged in contact underneath the bar, an eccentric provided thereon allowing to regulate the bend 50 of the same, a handle and an index on the outside of the casing adapted to indicate the position of the eccentric.

In testimony whereof I affix my signature in presence of two witnesses.

ADOLF LUDI.
